UNITED STATES PATENT OFFICE.

JOHN MURPHY, OF AUBURN, NEW YORK.

CARDING-MACHINE.

SPECIFICATION forming part of Letters Patent No. 248,495, dated October 18, 1881.

Application filed October 20, 1880. (No model.)

To all whom it may concern:

Be it known that I, JOHN MURPHY, of Auburn, in the county of Cayuga and State of New York, have invented certain new and useful 5 Improvements in Wool and Cotton Carding Machines, of which the following is a full, clear, and exact specification, reference being had to the accompanying drawings, in which—

Figure 1 is an end elevation, and Fig. 2, Sheet 10 2, a plan view, of a so-called "finisher" carding-engine with my improvement attached thereto, together with a diagonal self-feeding device, after the Apperley patent.

Similar letters of reference refer to like parts 15 in the two sheets of drawings.

Carding-engines as used in the manipulation of woolen stock are arranged in sets of three, known to manufacturers as the "first breaker," to which the material is fed as it comes from 20 the picker, the "second breaker," to which the material is fed in the form of drawings from the first breaker, and the "finisher," to which said material is fed in a similar form from the second breaker.

25 Much inconvenience and waste of stock has heretofore been occasioned (more especially where self-feeding appliances are used) by the uneven and lumpy nature of the outer threads of roving as they come from the outer rings of the doffer-cylinders of the finisher. This unevenness is caused by the looping, at either side of the feed-table, of the drawing as it is laid back and forth continuously by the automatic feed.

35 The object of my invention is to conveniently and readily correct this fault by stripping the main cylinder of this uneven stock and passing it back to the feed, so that it may with it be fed to the finisher, and thus prevent the waste 40 already mentioned.

In the drawings I have supposed the engine to be supplied with its full complement of feed-rolls, licker-in, strippers, workers, fancy, doffers, and customary condenser-head.

45 To effect the object to which I have alluded I make use of what I term a "third" doffer or worker, A, having two rings, B, of card-clothing, one placed at each end of the same, and of sufficient width to rob or strip from the outer 50 edges of the main cylinder C all of the uneven stock.

Attached to the arches D of the frame E are

brackets F, supporting two rolls, G and H, and the vibrating or rub roll J. This roll J is worked backward and forward upon the revolving rolls G and H by means of a bell-crank, K, attached to the end of the bracket F, and a link rod or pitman, L, which is actuated by the crank-wheel M, which in turn derives motion through the belt N, passing to the pulley O, 55 which is secured to the main-cylinder shaft P. The roll G derives its rotation from a band, Q, passing to a pulley, R, attached to the shaft of the worker S, and the latter is driven by a band from a pulley on the driving-shaft, the 60 roll H deriving its motion from a band, T, (or intermediate gearing, if desired,) passing to the end of the roll G. The third doffer, A, bears upon one end of its shaft a cog-wheel, 2, meshing with a pinion, 3, upon the stripper-shaft e. 70 The latter bears a pulley, 4, which is driven by the belt 5 from the driving-shaft P, whereby it will be seen that the motion of the driving-shaft is transmitted to the doffer A and stripper-shaft e, while the worker V is revolved by 75 a belt from a pulley fastened to the shaft of roller A.

In front of the rolls G, H, and J is a bail, Y, having a hanger-piece, Z. This bail is secured to two upright standards, aa, placed on either 80 side of the feed-table, and carries in its center a twisting-tube, b, which is caused to rotate by means of the band e, passing from a pulley, d, on the end of the stripper-shaft e, over the idler-pulleys ff, to a grooved pulley, g, forming 85 a part of the twister-tube b. In front of the twister-tube b are two short carrying-rolls, h h, supported in the hanger-piece Z, the upper roll being driven by a belt, i, deriving its movement from the feed motion, as shown, or otherwise, as most convenient. 90

Secured to the ceiling by brackets 1 are the carrier-pulleys j and k, the one deriving motion from the other by means of the cross-band l, and the pulley k driven by a belt from a pulley on the shaft of the stripper S. The pulley j carries the uneven strand of roving and the pulley k the drawing as it comes from the second breaker, together with the uneven strand. 95

The uneven roving is represented by m, the drawing by n, the diagonal feed by o, and the looped ends of the drawing, as it is fed upon the feed-table in a diagonal form, by p.

Having thus fully described my invention

and its several parts, I will proceed to set forth its operation.

The uneven stock, be it either cotton or wool, upon being taken from the outer edges of the 5 main cylinder by the rings of my third doffer or worker, is passed from these rings at once between the rolls G and H and the vibrating roller J, where each strand is partially rubbed or felted together, so as to give it some degree 10 of strength. From thence each strand passes under a guide-finger, q, to the twister-tube b, where the two strands are united or twisted together. From the twister-tube the now single strand passes through the carrying-rolls h 15 to the carrier-pulley j, from whence it is caused to pass and unite again with the drawing n, to be refed to the feed-table of the carding-engine, thus causing the fed stock to be more even than if composed of the single drawing feed alone.

It will thus be seen that the otherwise waste stock is taken from the main cylinder and caused continuously to pass therefrom to the

feed-table, avoiding that which has heretofore been of much annoyance and inconvenience to 25 workers of the material, rendering the feed evener and better than primarily given.

Having thus fully set forth my invention and its operation, what I claim is—

1. The combination, with the doffer A and 30 twisting-tube b, arranged substantially as shown, of the intermediate rolls, G H J, and guide-finger q, the roll J having a back-and-forth motion over the rolls G H, as and for the purpose described.

2. In a carding-machine, the combination, with the doffer A, of the rolls G H J, operating together as described, the guide-finger q, the twisting-tube b, the carrying-rolls h h, and the carrier-pulleys j k, all arranged substantially as and for the purpose specified. 35 40

JOHN MURPHY.
